UNITED STATES PATENT OFFICE

121,309

DESIGN FOR A TOY LIGHTHOUSE COMBINATION

Sayward O. Talmadge, Richmond Hill, N. Y.

Application April 9, 1940, Serial No. 91,563

Term of patent 7 years

To all whom it may concern:

Be it known that I, Sayward O. Talmadge, a citizen of the United States of America, residing at 104-54 123rd Street, Richmond Hill, Long Island, in the county of Queens and State of New York, have invented a new, original, and ornamental Design for a Toy Lighthouse Combination, of which the following is a specification, reference being had to the accompanying drawing, forming a part thereof.

Figure 1 is a front elevational view of a toy lighthouse combination, showing my new design; and

Figure 2 is a side elevational view thereof.

I claim:

The ornamental design for a toy lighthouse combination, as shown.

SAYWARD O. TALMADGE.
